COMBINATION ELECTRIC SWITCH AND
CIRCUIT BREAKER

Stephen S. Grady, New York, N. Y.

Application April 2, 1946, Serial No. 658,895

4 Claims. (Cl. 175—294)

1

This invention relates to electric switches in general, and more especially to combination electric switches and circuit breakers.

Among the objects of the present invention it is aimed to provide an improved combination electric switch and circuit breaker such as used in power stations and the like whereby at will the circuit may be interrupted of a three phase circuit by mere movement of a handle, and which circuit in turn will be interrupted by an overload in any conductor of the three phase circuit without materially actuating the handle if at all.

It is still another object of the present invention to provide an improved combination electric switch and circuit breaker for controlling a three phase circuit whereby the circuit may be manually interrupted by actuation of a handle and in turn also interrupted in case of an overload in any one or more of the conductors of the three phase circuit without actuating the handle so that an attendant may be effectively protected against injury should he be holding, or be in the path of movement of, the handle at the time the circuit is interrupted by an overload, which circuit breaker may be set in anticipation of an overload interruption after which the handle may be actuated into and out of current interrupting position without affecting the overload circuit breaking mechanism.

It is still another object of the present invention to provide an improved combination electric switch and circuit breaker which includes a handle for manually actuating an interposer to interrupt the circuit at will, a fuse interposed in the conductor when the circuit is established, and an electric circuit breaker for automatically actuating the interposer to interrupt the current when the fuse has been blown or destroyed, which fuse will predetermine the maximum load to be carried, and which will short circuit the circuit 40 breaking mechanism so that the circuit breaking mechanism may be sensitive to a very low amperage not in any way related to the maximum load to be carried by the conductor.

It is still another object of the present invention to provide an improved combination electric switch and circuit breaker for a three phase circuit including an interposer operatively connected to a manually operated handle to actuate the interposer to interrupt the circuit at will, a circuit breaker operatively connected to actuate said interposer in case of an overload, means for operatively connecting said manually operated handle to set said circuit breaker in anticipation of an overload, and a plurality of ammeters,

2

one for each conductor of the three phase circuit which can be readily inspected by the attendant to determine the relative flow of current in the three conductors of the three phase circuit.

With combination electric switches and circuit breakers, especially for light control stations or power plants where three conductors are associated in three phase circuits, a single switch 10 has been extensively used simultaneously to interrupt or establish the circuit through the three conductors. While good practice requires that the flow through all conductors be maintained substantially equal to one another, it is practically impossible to maintain the load equal in all three conductors. Consequently, if the fuses for the three conductors have been selected to carry a predetermined load, obviously when an overload occurs the critical point is not 15 reached in all three conductors at the same time, but generally reached in one conductor first. In view of the foregoing, it is an object of the present invention to provide a combination switch and circuit breaker to interrupt the current in all 20 three conductors whenever an overload occurs in any one of them so that the attendant or operating engineer will not by inadvertence be injured by the current flowing through the electrode of which the fuse has not been blown.

It is still another object of the present invention to provide a door which cannot be opened to gain access to the switch until the current in all three conductors has been effectively interrupted, when the switch used is made in accordance with the 30 combination electric switch and circuit breaker of the present invention and the switch is used with the three conductors of a three phase circuit.

It is still another object of the present invention to provide an improved electric switch and circuit breaker for the three conductors of a three phase circuit associated with an ammeter and an electro-magnet for each conductor for initiating the actuation of the circuit breaker when any of the three fuses, due to an overload, is blown in 40 which the circuit through the electro-magnet is not established unless the needle of the ammeter registers zero which will occur momentarily when the fuse for any conductor is blown due to an overload, the energizing of the electro-magnet 45 initiating the actuation of the circuit breaker for all three conductors, as a result of which arrangement, the electro-magnet is definitely protected against injury in case of an overload and in turn a fuse responsive to a predetermined critical 50 point corresponding to a predetermined overload

can be selected without regard to leakage through the electro-magnet.

These and other features, capabilities and advantages of the invention will appear from the subjoined detail description of one specific embodiment thereof illustrated in the accompanying drawings, in which

Fig. 1 is a fragmental front elevation of a casting to house a plurality of combination switches and circuit breakers made according to the present invention.

Fig. 2 is a front elevation of a combination electric switch and circuit breaker typical of one unit part in section.

Fig. 3 is a section on the line 3—3 of Fig. 2.

Fig. 4 is a fragmental enlarged section on the line 4—4 of Fig. 2.

Figs. 5, 6 and 7 are fragmental sections similar to the section shown in Fig. 1, showing successive positions of the main actuating means, but on a smaller scale than that shown in Fig. 4.

Fig. 8 is a section on the line 8—8 of Fig. 3.

Fig. 9 is a perspective with parts broken away of the interposer.

Fig. 10 is a fragmental perspective of one portion of a unit.

In the embodiment shown, see Fig. 1, there is illustrated a succession of switch housings 1, 2 and 3, only three being shown in this instance, illustrating in a general way the position of these housings in a control room for a plant in which the housing 1 may house or encase the combination electric switch and circuit breaker of one three phase unit, the housing 2 of another three phase unit, and the housing 3 of still a third three phase unit. Access to the electric switch is afforded through the door 4 pivotally connected at its lower end, in the present instance, and provided with a latch 5 at its upper end for anchoring the door 4 in place. The door 4 has a window 6 which may be equipped with a sheet of glass to facilitate inspecting the ammeters 7, 8 and 9, but bar tampering with the same when the door 4 is in closed position. The door 4 is also provided with two slots 10 and 11 to clear the outer ends 12 of the actuating plates 13 and also the extensions 14 for the handle 15. These slots 10 and 11 are just large enough to clear the extensions 14 when current is interrupted, that is, when the extensions 14 are shown in the position illustrated in Fig. 5, but bar the opening of the door 4 when the extensions 14 are in the raised position or circuit making position, that shown in Fig. 3. In this way, the attendant will be assured that the current is interrupted before he opens the housing.

In the housing 1, which is typical of any number of housings, such as 2 and 3, there are provided two supporting metal bars or angle irons 115 and 116 to which are secured the bars 17 and 18 composed of a suitable insulating material, see Figs. 2 and 3, across which bars 17 and 18 are secured the cross bars 19 and 20 composed of a suitable insulating material. The bars 17 and 18 are preferably spaced from one another as shown in Fig. 2, and the bars 19 and 20 preferably extend beyond the bars 17 and 18 to form three spaced supporting areas. In the present instance, between the bars 17 and 18 and the cross bar 19, there are secured the bus bars 21, 22 and 23 which are provided in the present instance with the brackets 24, 25 and 26 at their upper ends to receive the electrodes 27, 28 and 29, respectively, and to the outer face of the cross bar 19 there are secured the upper ends of

the flexible laminated contact members 30, 31 and 32 and extending down from the upper ends of the flexible members 30, 31 and 32 there are provided the bus bars 33, 34 and 35, respectively, which in turn are spaced from the upper ends of the bus bars 36, 37 and 38, respectively, mounted on the insulated base plates 39, 40 and 41, respectively, extending up between the cross bar 20 and the bus bars 36, 37 and 38, respectively. The bus bars 36, 37 and 38, however, are preferably secured to the cross bar 20 by screws or bolts which extend through the flanges of the brackets 42, 43 and 44, respectively, and the adjacent base plates 39, 40 and 41, respectively, to which brackets 42, 43 and 44 in turn are connected the electrodes 45, 46 and 47, respectively.

It is of course obvious that the present invention is applicable to a combination switch and circuit breaker for a single conductor as well as a plurality of conductors without departing from the general spirit of the invention, although the application of the present invention to the three conductors of a three phase circuit presents features peculiar to a three phase circuit and distinguishable from a switch associated with a single conductor.

It is of course also obvious, Fig. 10, that the electrode 27 and electrode 45 are associated with the bracket 24, bus bar 21, flexible contact 30, bus bar 33, insulated plate 39, bus bar 36 and bracket 42, that the electrode 28 in turn, Fig. 3, is associated with the electrode 46 through the bracket 25, bus bar 22, flexible contact 31, bus bar 34, insulated plate 40, bus bar 37 and bracket 43, and that the conductor 29, Fig. 2, is associated with the conductor 47 through the bracket 26, bus bar 23, flexible conductor 32, Fig. 8, bus bar 35, insulated plate 41, bus bar 38, Fig. 2, and bracket 44.

40 The bus bar 33 and bus bar 36 are connected by the fuse plate 48, the bus bar 34 in turn is connected to the bus bar 37 by the fuse plate 49, and the bus bar 35 is connected to the bus bar 38 by the fuse plate 50. These fuses 48, 49 and 50 are of course selected to blow or fuse, in the conventional way, when a predetermined load is reached. If the normal load of the several conductors is below 1000 amperes, then obviously the fuses 48, 49 and 50 would be selected to blow when a load of approximately 1100 amperes is reached.

For interrupting the circuit in any one of the conductors there is provided an interposer 51 which is operable either by the handle 15 manually to interrupt or establish the current, or else automatically operated whenever any one of the fuses 48, 49 or 50 is blown or broken. The interposer 51, Fig. 9, in the present instance, consists essentially of a plate of insulated material common to all three conductors. The plate, in the present instance, has recessed cheeks 52, 53 and 54 adjacent the openings 55, 56 and 57, respectively. This plate 51 in actual practice is positioned so that either the cheek plates 52, 53 and 54 are interposed between the bus bars 21, 22 and 23, and flexible conductors 30, 31 and 32, respectively, to interrupt the current passing from the bus bars 21, 22 and 23 to the flexible conductors 30, 31 and 32, respectively, or else positioned so that the openings 55, 56 and 57 register, see Fig. 10, with the ends of the bus bars 21, 22 and 23 and flexible conductors 30, 31 and 32, respectively, to establish a circuit or contact between the bus bars 21, 22 and 23, and flexible conductors 30, 31 and 32, respectively. In order to effect an inti-

mate engagement between the bus bars 21, 22 and 23 and the flexible conductors 30, 31 and 32, respectively, the plate 51 is provided with three pairs of spring arms, such as the spring arms 58 and 59, the spring arm 58 having at its ends the rollers 60 and the spring arm 59 having at its ends the rollers 61. These spring arms 58 and 59, see particularly Fig. 3, engage the outer faces of the bus bar and flexible conductor, such as the bus bar 22 and flexible conductor 31, to press the 10 same into intimate engagement with one another when the interposer 51 is elevated into the circuit making position shown in Fig. 3.

The mechanism whereby the handle 15 may be manipulated manually to actuate the interposer 15 51 to establish and interrupt the circuit will now be described.

The handle 15, as aforesaid, is mounted on the extensions 14 of the plates 13. Since both plates 13 are identical to one another, a description and explanation of the plate 13 cooperating with the slot 11 alone will be undertaken and suffice for both of them. In Fig. 4, this plate 13 is mounted on the pin 62 journalled in the plate 63, secured to the cross bars 19 and 20. This plate 13 has an arcuate slot 64 concentric to the pin 62. This plate 13 has a pin 65 in the projection 66 and an opening 67 near the recess 68. The recess 68, and more particularly the shoulder 69 of the recess 68, is adapted to cooperate with the pin 70 on the plate 63 to determine the lowest position of the plate 13. In this lowest position when the cover 4 is removed, the opening 67 receives the pin 71 formed on the spring arm 72 secured to the plate 63 so that the pin 71 extends through the opening 73 in the plate 63 into the opening 67 in the plate 13. When the plate 13 is actuated into the position shown in Fig. 5, where the pin 71 registers with the opening 67, then if the door 4 is opened, it will clear the spring arm 72 and permit the arm 72 to project the pin 71 into the opening 67 in the plate 13. When the pin is so projected into the opening 67 in the plate 13, it will anchor the plate 13 and its companion plate 13 from movement about its pivot 62, and not again to establish the circuit interrupted by the interposer plate 51 until the spring arm 72 has been deflected to withdraw the pin 71 from the opening 67 when the plates 13 will be free again to raise the interposer plate 51 into the circuit making position illustrated in Fig. 4, where the openings 55, 56 and 57 register with the free ends of the bus bars 21, 22, 23 and the free ends of the flexible contacts 30, 31 and 32, respectively.

In order to enable the plates 13 to move the interposer plate 51, each of the plates 13 is operatively connected to a link 74 which link is provided with a slot 75 slidably mounted on the pin 76 extending from the plate 63 through the arcuate slot 64 in the plate 13. The link 74 has a finger 77 extending into an opening 78 in the interposer plate 51. The interposer plate 51 is provided with two openings 78 for the finger 77 of each of the links 74. Each link 74 is indirectly actuated by a plate 13 due to the spring 79 connected to the pin 80 on the plate 13, the other end of which spring 79 is connected to the pin 81 on the finger 77. Preferably in the interest of assembly, the plate 13 and link 74 are disposed on one side of a plate 63 and the spring 79 is disposed on the other side of the plate 63, the pin 80 extending beyond the front free edge of the plate 63 and the pin 81 extending through the recess 82 in the plate 63 and in the present instance just forwardly of the interposer plate 51. The spring 79,

plate 13 and link 74 form a toggle, as a result of which, when the plate 13 is moved into the position shown in Fig. 5, about its pin 62, the spring 79 will swing the link 74 into the position shown in Fig. 5. On the other hand, when the plate 13 is moved into the position shown in Fig. 4 from the position shown in Fig. 5, where the pin 80 of the spring 79 moves upwardly relative to the pin 76 on which the link 74 is slidably mounted, the spring 79 will actuate the link 74 upwardly into the position shown in Fig. 4. For actuating the link 74 in case of a short circuit, the coil spring 83 wound around the pin 84, secured to the plate 63 is provided, one end of the coil spring being biased against the stop 85 formed in the plate 63, the other free end 86 of which having a lip 87 to cooperate with the latch bar 88 fixedly mounted on the shaft 89. The latch bar or plate 88 on the shaft 89 is biased into the position shown in Fig. 4 by the spring 90 shown in Fig. 2, secured to the shaft 89, wound around the same, and with one end yieldable in engagement with the pin 91 extending from one of the plates 63 nearer to the left hand side of the unit. The link 74 has an arm 92 extending from one end thereof, and provided with a pin 93 to cooperate with the finger 86 of the spring 83. The plate 13, see Fig. 4, is also provided with a pin 94, normally engaging the edge 95 of the link 74, and positioned to enter the recess 96 in the link 74 adjacent the slot 75.

In practice, when an overload occurs, the latch 88 is rocked with its shaft 89 so that the latch 88 clears the lip 87 and allows the finger 86 of the spring 83 to strike the pin 93 of the link 74. Initially, this lateral movement of the link 74 will cause the link 74 to slide on the pin 76 so that the pin 76 enters the front end of the slot 75, when the recess 96 will register with the pin 94, and due to the continuing urge of the spring arm 86 will cause the link 74 to move into the position shown in Fig. 6, where the pin 94 registers with the recess 96, and then urge the link 74 into the position shown in Fig. 7, carrying with it the interposer plate 51 into circuit breaking position. In order to restore the lip 87 in biased position on the latch plate 88, the handle 15 of the plate 13 may then be depressed when the plate 13 will cause its pin 65, see Figs. 7 and 5, to engage the arm 86 of the spring 83 and deflect it to pass the latch 88, until the lip 87 again rests on the front end of the latch 88 as shown in Figs. 5 and 4.

In this depressed position of the handle 15, however, the interposer plate 51 will still be in circuit breaking position. At this time, however, as aforesaid, when the cross piece of the handle 15 is removed, the slots 10 and 11 will clear the extensions 14 of the plates 13 and allow the door 4 to be opened. Immediately, however, that the door is opened, the pin 71 of the spring 72 will snap into the opening 67 of one of the plates 13 and anchor the plates 13 against further actuation thereby protecting the attendant from injury should he accidentally attempt to move the plates 13 into circuit making position. In other words, the locking of the plates 13 in this circuit breaking position will require the attendant to deflect the spring arm 72 and thereby bring to his attention the fact, if he is acquainted with the switch, that the switch in such anchored position is in circuit breaking position and may only be moved into circuit making position when the spring arm 72 is deflected.

After an overload has actuated the interposer plate 51 into the position shown in Fig. 7, and

the plates 13 have been moved into the position shown in Fig. 5, to reset the spring arm 86 on the latch plate 88, the position shown in Fig. 5, and the door 4 has been opened, the fuses which may have been blown may be restored while the circuit is still broken, thereupon the door 4 again closed and then only the handle 15 raised into the position shown in Fig. 4, again to establish the circuit.

From the foregoing, it will appear that with two plates 13 each provided with a spring 83 and a link 74 operatively connected to the interposer plate 51, the handle 15 may be actuated manually to establish and interrupt the circuit. In other words, disregarding the latch 88 and its circuit breaker association, when the spring arm 86 rests on the latch 88, if the handle 15 is elevated into the position shown in Fig. 3, the interposer 51 will assume the position shown in Fig. 4 when the circuit will be established, and in turn when the handle 15 is depressed so that the plates 13 assume the position shown in Fig. 5, the interposer 51 will descend into circuit breaking position, all without affecting the position of the spring arm 86 on the latch 88.

The operation of the latch 88 will now be described. The latch 88, as aforesaid, is mounted on the shaft 89, which in the present instance has three arms 97, one for each electro-magnet 98 mounted on the bus bars 33, 34 and 35 but insulated therefrom by the insulated plates 99. The arms 97 preferably have formed at their ends a piece of soft iron 100 to facilitate magnetic action on the same by the electro-magnets 98 when energized. The electro-magnets 98 are insulated from the bus bars 33, 34 and 35, and consequently when circuits are established through the bus bars 33, 34 and 35 for normal operation, the electro-magnets 98 will not be energized. Preferably above the electro-magnets 98, the bus bars 33, 34 and 35 are provided with the ammeters 101. These ammeters 101, each consist essentially of a plate 102 having a main section 103 and an auxiliary section 104 extending parallel to the section 103, but spaced therefrom by the web 105. The section 104 is shorter than the section 105 to afford access to the fastening screws for the section 103 and to provide an area for graduation marks which are disposed in an arcuate line to align with the path of movement with the free end of the needle 106, all as shown and more fully described in my co-pending application, Serial No. 606,368, filed July 21, 1945, now Patent No. 2,430,465. The ammeters 101 in the present instance, however, are distinguished from the ammeters disclosed in my aforesaid co-pending application in that the zero position of the needle 106 coincides with the position of the needle 106 where it engages the pin 107 insulated from a bus bar 33, 34, 35 by the insulated jacket 108. The pin 107 of each ammeter 101 is connected with an electro-magnet by the conductor 109. The electro-magnet in turn is connected with a bus bar 36, 37, 38 by a conductor 110.

From the foregoing, it will thus appear that when a fuse 48, 49 or 50 is blown or fused to interrupt the current between a pair of bus bars 33—36, 34—37, or 35—38, then the current will be momentarily interrupted in such circuit and cause the needle 106 to drop into position where it will engage the pin 107. Since the needle 106 is electrically connected to a bus bar 33, 34, 35 immediately that the needle 106 strikes the pin 107, the current will momentarily rush from the needle 106 through the electro-magnet 98 to

5 energize the same, in turn to attract the armature 100 and rock the shaft 89 in turn to swing the latch plates 88 clear of the fingers 87 when the arms 86 of the springs 83 will strike the pins 93 as aforesaid, so that from the position shown in Fig. 4, the links 74 will first assume the position shown in Fig. 6 and then move into the position shown in Fig. 7 where as aforesaid they will have actuated the interposer plate 51 into circuit breaking position.

10 From the foregoing it will be seen that due to this positioning of the ammeters 101, the full charge during normal operation will always flow through the respective fuses 48, 49 and 50 and no 15 leakage of current will be deflected through the electro-magnets 98. Still furthermore, since the 20 energization of electro-magnets 98 will only require a momentary contact of a needle 106 with a pin 107 to rock the shaft 89, the overload current can never develop full amperage when passing through the electro-magnets 98, and consequently the electro-magnets will at all times be 25 fully protected against injury.

From the foregoing, it will also appear that the 25 recesses 96 receiving the pins 94 of the plates 13 will allow the links 74 to actuate the interposer plate 51 without materially affecting, if at all, the position of the plates 13, so that if an attendant should be standing next to the handle 15 30 when an overload is registered to actuate the circuit breaker, he can, under no circumstances, be injured due to movement of the handle 15 when the circuit breaks.

35 Preferably the plates 13 and associated links 74 and partitions 63 are spaced from the circuit breaker mechanism, including the electro-magnets 98 and fuses 48, 49 and 50 by the partitions 108 composed of insulated material extending from the front face of the interposer plate 51. 40 Preferably also, the partitions 109 composed of insulated material extending from the rear face of the interposer plate 51 insulate the fingers 71 of the links 74 from the bus bars 21, 22 and 23, so that each conductor unit, including electrodes 45 27—45, 28—46, and 29—47 are insulated from one another effectively to prevent any arcing between the adjacent conductor units.

50 It is obvious that various changes and modifications may be made to the details of construction without departing from the general spirit of the invention as set forth in the appended claims.

55 It is, of course, obvious that the electro-magnets 98 instead of being connected to the pins 107 by the conductors 109 could be directly connected to the bus bar 33 without departing from the general spirit of the invention in which case, however, leakage could not be effectively barred as is the case when the electro-magnets 98 are connected to the pins 107.

60 I claim:

65 1. In a circuit breaker for two conductors, the combination of a first bus bar for one conductor, a second bus bar, a contact connected to said second bus bar with its free end normally engaging said first bus bar, a third bus bar connected to the other conductor, means including a fuse for connecting the second bus bar to said third bus bar, an interposer slidably mounted between said first bus bar and contact, a lever operatively connected to said interposer, a spring biased in inoperative position and when released operatively associated to actuate said lever in turn to actuate said interposer into circuit breaking position, a latch for anchoring said spring in biased position, an electro-magnet positioned when

energized to actuate said latch to release said spring, an ammeter including a pivotally mounted needle electrically connected to said second bus bar to record the amperage of the current flow when said fuse is intact, a pin insulated from said ammeter, a conductor connecting said pin to said electro-magnet, and a second conductor connecting said electro-magnet to said third bus bar, said needle engaging said pin when the current is interrupted by the blowing of said fuse, in turn momentarily to establish a circuit after the fuse is blown between said ammeter and said third bus bar thereby to energize said electro-magnet in turn to actuate said latch.

2. In a circuit breaker for a three phase circuit having three pairs of conductors, a first bus bar and a second bus bar for one conductor of each pair, a contact for each of said pairs of conductors and connected to its associated second bus bar with its free end normally in engagement with its associated first bus bar, a third bus bar for the other conductor of each pair, a fuse connecting each associated second bus bar with its associated third bus bar, an interposer common to all three pairs of conductors slidably mounted between said first bus bars and said contacts, an actuating device including links operatively connected to said interposer, springs for actuating said links into circuit breaking position, a latch for anchoring said springs in inoperative position, an ammeter including a needle for each pair of conductors electrically connected to its associated second bus bar and in position to record the amperage of the circuit passing through a pair of conductors when its associated fuse is intact, a pin for each ammeter insulated from the same, an electro-magnet for each ammeter, a conductor connecting each pin to one of said electro-magnets, a second conductor connecting each electro-magnet to its associated third bus bar, the needle of each ammeter when the current of its associated circuit has been interrupted by the blowing of a fuse receding to zero and engaging the pin momentarily to re-establish the circuit through its associated pair of conductors, a shaft for said latch, armatures on said shaft, one for each electro-magnet to be attracted by an electro-magnet when energized to release said latch to free said springs to actuate said interposer whereby the blowing of a fuse associated with any pair of conductors will initially interrupt the circuit by said interposer through all three pairs of conductors.

3. In a circuit breaker for two conductors, the combination of a first bus bar for one conductor, a second bus bar, a contact connected to said second bus bar with its free end normally engaging said first bus bar, a third bus bar connected to the other conductor, means including a fuse for connecting the second bus bar to said third bus bar, a second means for interrupting the passage of current from said first bus bar to said contact, a lever operatively connected to said second means, a spring biased in inoperative position and when released operatively associated to actuate said lever in turn to actuate said second means into circuit breaking position, a latch for anchoring said spring in biased position, an electro-magnet positioned when energized to actuate said latch to release said spring, an ammeter including a needle electrically connected to said second bus bar, a pin insulated from said am-

meter, said needle being deflected from said pin by the current flow when said fuse is intact, a conductor connecting said pin to said electro-magnet, and a second conductor connecting said electro-magnet to said third bus bar, said needle engaging said pin when the current is interrupted by the blowing of said fuse, in turn momentarily to establish a circuit, after the fuse is blown, between said ammeter and said third bus bar thereby to energize said electro-magnet in turn to actuate said latch.

4. In a circuit breaker for a three phase circuit having three pairs of conductors, a first bus bar and a second bus bar for one conductor of each pair, a contact connected to its associated second bus bar with its free end normally in engagement with its associated first bus bar, a third bus bar for the other conductor of each pair, a fuse connecting its associated second bus bar with its associated third bus bar, a means common to all three pairs of conductors for interrupting the passage of the current between their first bus bars and their contacts, an actuating device including links operatively connected to said means, springs for actuating said links into circuit breaking position, a latch for anchoring said springs in inoperative position, an ammeter including a pivotally mounted needle for each pair of conductors electrically connected to its associated second bus bar responsive to the amperage of the circuit passing through a pair of conductors when its associated fuse is intact, a pin for each ammeter insulated from the same, said needle being deflected from said pin when its associated fuse is intact, an electro-magnet for each ammeter, a conductor connecting each pin to one of said electro-magnets, a second conductor connecting each electro-magnet to its associated third bus bar, the needle of each ammeter when the current of its associated circuit has been interrupted by the blowing of a fuse swinging into engagement with its associated pin momentarily to re-establish this circuit through its associated pair of conductors, a shaft for said latch, armatures on said shaft, one for each electro-magnet to be attracted by an electro-magnet when energized to release said latch to free said springs to actuate said means whereby the blowing of a fuse associated with any pair of conductors will initially interrupt the circuit by said means through all three pairs of conductors.

STEPHEN S. GRADY.
